(57) **CLAIM**

The ornamental design for a sprayer shroud, as shown and described.

DESCRIPTION

FIG. 1 is an isometric view of the sprayer shroud showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed lines are included for the purpose of illustrating portions of the sprayer shroud, bottle and belt clip that form no part of the claimed design. The dash-dot-dash-dot broken lines of FIGS. 1-5 depict the lower boundary of the claimed design. FIG. 7 forms no part of the claimed design.
